UNITED STATES PATENT OFFICE

2,010,680

WINDOW LIFT

Lewis B. Van Leuven, Westfield, N. J.

Application November 17, 1933, Serial No. 698,424

9 Claims. (Cl. 254—131)

This invention relates to devices for use in raising or jacking various body members, such for example, as in raising a window sash or to free a sticking or binding sash to permit the opening thereof; and the object of the invention is to provide a tool or implement of the class described comprising a post or standard with a lever adjustable with respect to said standard and pivotally mounted in connection therewith to provide for the operation of said lever; a further object being to provide means for disposing the pivot at different points longitudinally of the lever to increase or decrease the length of the jaw or head end portion thereof with respect to the pivot; a further object being to provide a lever consisting of relatively collapsible parts which are further collapsible with respect to the post or standard to provide a compact unit of the entire device; a further object being to provide a device wherein the separate parts are preferably formed from sheet metal whereby the same may be produced at a very reasonable manufacturing cost; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of the device made according to my invention, indicating one method of its use.

Fig. 2 is a section on the line 2—2 of Fig. 1.

Fig. 3 is a section on the line 3—3 of Fig. 1.

Fig. 4 is a longitudinal section through the device showing the parts in a collapsed position.

Fig. 5 is a plan view of a blank from which one of the parts of my improved device is formed; and,

Fig. 6 is a detail view of a part of a modified form of lever which I may employ.

In the accompanying drawing, I have indicated at 10 one part, namely the stock, post or standard of one of my improved devices, and at 11 a lever. For the purpose of illustrating one method of carrying my invention into effect, I have indicated in Fig. 1 of the drawing, at 12, a window sash having a hand grip 13 by means of which the window may be raised and lowered. At 14, I have shown part of the window frame and at 15 the window sill. The part 10 is made from a sheet

metal blank substantially similar to that shown in Fig. 5 of the drawing and consisting of two elongated plates 16, 16a having side flanges 17 which are foldable at right angles to the plates 16, 16a to form strengthening ribs as clearly seen in Fig. 3 of the drawing.

The plates 16 and 16a join each other in a crosshead 18 including a part 18a foldable beneath the part 18 so as to reinforce the upper portion of the post 10 and further to provide an opening 19 at the top of the post receiving a lever 11 when in collapsed position as in Fig. 4 of the drawing. The ends of the plates 16, 16a are folded to form relatively wide extending flanges 20 which form supporting feet for the post or standard, and it will be noted that the lower ends of the flanges 17 rest upon the upper surfaces of the flanges or feet 20 to reinforce the latter. Facings 21 of cushioning material are glued or otherwise secured to the lower surfaces of the flanges on the feet 20 so as to prevent marring of the sill 15 or other surface upon which the device is placed.

Each plate 16, 16a is cut out to form an elongated aperture 22 having an upper offset 23, a lower offset 24 and an intermediate offset 25. It will be understood that the apertures 22 and offsets 23, 24 and 25 are in alinement with each other when the plates 16, 16a are in folded relation with respect to each other, and said offsets 23, 24 and 25 form bearings for a pivot pin 26 having a head 26a at one end, a washer 26b at the other end held in place by a cotter pin or the like 26c so that the pin 26 is capable of mounting in one of a number of apertures 27 formed longitudinally of the lever 11 or the part 28 thereof.

The part 28 of the lever is twisted at one end as seen at 29 to form a relatively wide jaw, head or member 30, the latter being formed by curling or rolling the end of the lever which forms a substantially hooked end. This jaw or head 30 is suitable for engagement with the hand grip 13 and any other article, in the operation of raising or jacking the same and by virtue of its offset or hooked contour, will be retained against displacement from the article.

The lever 11 includes a handle part 31 which is pivoted to the part 28 as seen at 32. The part 31 has a projecting stop member 33 engaging a recess 34 in the part 28 to limit the swinging movement of the parts with respect to each other in one direction, whereas the part 31 is capable of movement into a position paralleling the part 28 on the pivot 32. The part 31 is preferably offset as seen at 31a, note Fig. 3, to clear the

flanges 17 when the parts are in collapsed position as seen in Fig. 4 of the drawing.

The lower ends of the plates 16, 16a of the standard are joined at one side by a rivet or coupling pin 35 which prevents a spreading of said plates, and at the same time permits the swinging movement of the lever into the space 36 between adjacent faces of the plates when in the collapsed position shown in Fig. 4.

10. In the use of the tool, it will be understood that the part 28 of the lever may be raised and lowered in the post or standard 10 to dispose the pivot pin 26 in either one of the offsets 23, 24 and 25, the same being shown in the offset 25 in the construction shown in Fig. 1. When so positioned, the head 30 is placed beneath the hand grip 13 of the sash 12 and downward pressure is applied on the part 31 of the lever which will operate to disengage a binding or sticking sash 12. In 15 this connection, it will also be understood that the pin 26 may be disposed in either one of the apertures 27 to increase or decrease the length of the protruding end of the lever part 28 with respect to the standard, or as seen in Fig. 6 of the drawing, a lever part 28a similar to the part 28 may have in its lower edge a series of recesses 37 to engage the pin 26 to provide this adjustment without removing the pin 26 from the standard or body 10.

20. It will be understood that while I have illustrated the device as used for the purpose of raising or freeing window sashes, the same may be used for any other purpose as a jack or lifting tool, and while I have shown certain details of 25 construction for carrying my invention into effect, it will be understood that I am not necessarily limited in these respects, and various changes in and modifications of the construction herein shown and described may be made within the scope of the appended claims without departing from the spirit of my invention or sacrificing its advantages.

Having fully described my invention, what I claim as new and desire to secure by Letters 30 Patent, is:

1. A device of the class described comprising a standard consisting of parallel plates spaced apart to form an elongated recess therebetween, a relatively long lever disposed in the recess of said standard, means for pivotally supporting one end portion of the lever to said standard to dispose one short end of the lever outwardly of the standard, said short end having a transversely offset member, and said lever including relatively movable parts adapted to be collapsed to dispose the same in substantially parallel relation with each other and to the longitudinal plane of the standard, and one part of said lever disposed within the recess of the standard when in collapsed position.

2. A lift or jack device of the class described comprising a post, a relatively long lever, means for pivotally and adjustably supporting the lever in connection with said post and said lever including pivotally coupled parts adapted to be folded into parallel relation with respect to each other, one part being disposed within the post and the other part being offset to clear the post to dispose said parts of the lever substantially, 40 parallel to the longitudinal plane of the post when not in use.

3. A device of the class described comprising a stock or body, a relatively long lever, means for pivotally supporting the lever in connection with 45 said body, said body comprising parallel sheet

metal plates, means at the ends of said plates for coupling said plates together to form a space therebetween opening through the front, back, and partially through the top and bottom of said body for reception and movement of said lever, and means extending longitudinally of said plates for reinforcing the same.

4. A device of the class described comprising a stock or body, a relatively long lever, means for pivotally supporting the lever in connection with 50 said body, said body comprising parallel sheet metal plates, means at the ends of said plates for coupling said plates together to form a space therebetween opening through the front, back, and partially through the top and bottom of said body for reception and movement of said lever, means extending longitudinally of said plates for reinforcing the same, said lever comprising an 55 elongated strip of metal, one end of which is curled to form the cylindrical head and the lever adjacent the head being twisted to dispose said head transversely with respect to the lever.

5. In a lift device of the class described, a standard fashioned from a single strip of metal, each end portion of the strip being of similar construction and comprising an elongated plate having side flanges and an elongated aperture having a plurality of offset sockets, the strip being folded centrally to dispose said plates in parallel and spaced relation with respect to each other, and means at one lower corner portion of said plates for coupling and spacing the same in forming said standard with the aperture and offset sockets of said plates disposed in common transverse alinement.

6. In a lift device of the class described, a standard fashioned from a single strip of metal, each end portion of the strip being of similar construction and comprising an elongated plate having side flanges and an elongated aperture having 40 a plurality of offset sockets, the strip being folded centrally to dispose said plates in parallel and spaced relation with respect to each other, means at one lower corner portion of said plates for coupling and spacing the same in forming said 45 standard with the aperture and offset sockets of said plates disposed in common transverse alinement, the lower ends of said plates including integral flanges extending outwardly and laterally with respect to the plates to form supporting 50 legs, and facings of cushioning material arranged on the lower surfaces of said supporting legs.

7. In a lift device of the class described, a standard fashioned from a single strip of metal, each end portion of the strip being of similar 55 construction and comprising an elongated plate having side flanges and an elongated aperture having a plurality of offset sockets, the strip being folded centrally to dispose said plates in parallel and spaced relation with respect to each 60 other, means at one lower corner portion of said plates for coupling and spacing the same in forming said standard with the aperture and offset sockets of said plates disposed in common transverse alinement, and the central portion of the strip being cut out where folded to form at the upper end of the standard a large opening extending through the top and one side of the standard.

8. In a lift device of the class described, a standard fashioned from a single strip of metal, each end portion of the strip being of similar construction and comprising an elongated plate having side flanges and an elongated aperture having a plurality of offset sockets, the strip be- 70

ing folded centrally to dispose said plates in parallel and spaced relation with respect to each other, means at one lower corner portion of said plates for coupling and spacing the same in forming said standard with the aperture and offset sockets of said plates disposed in common transverse alignment, the central portion of the strip being cut out where folded to form at the upper end of the standard a large opening extending through the top and one side of the standard, and an elongated sheet metal lever having a pivot pin adapted to be arranged in the apertures and offset sockets of said plates in adjusting the lever vertically in said standard, and the free end of the lever including a cylindrical head offset laterally with respect to said lever.

9. In a lift device of the class described, a standard fashioned from a single strip of metal, each end portion of the strip being of similar construction and comprising an elongated plate having side flanges and an elongated aperture having a plurality of offset sockets, the strip being folded centrally to dispose said plates in par-

allel and spaced relation with respect to each other, means at one lower corner portion of said plates for coupling and spacing the same in forming said standard with the aperture and offset sockets of said plates disposed in common transverse alignment, the central portion of the strip being cut out where folded to form at the upper end of the standard a large opening extending through the top and one side of the standard, an elongated sheet metal lever having a pivot pin adapted to be arranged in the apertures and offset sockets of said plates in adjusting the lever vertically in said standard, the free end of the lever including a cylindrical head offset laterally with respect to said lever, and said lever including a handle portion offset with respect to the lever proper and pivoted thereto to dispose the handle portion in common transverse alignment with the lever and both parts of the lever in parallel relation to the standard when the parts are in collapsed position.
